Specification of Letters Patent. Patented Dec. 24, 1912.

Application filed May 29, 1911. Serial No. 630,072.

To all whom it may concern:

Be it known that we, ALBERT L. MARSH and JOSHUA PATRICK, citizens of the United States, residing at Detroit, in the county of Wayne and State of Michigan, have invented a new and useful Improvement in Recording Devices, of which the following is a specification.

This invention relates, generally stated, to improvement in registering, electric current measuring, and the like devices which operate to deline, upon a suitable sheet or chart, a comprehensive and permanent chronological record of the operations, including variations in the operations, of apparatus with which it is connected.

The object is to provide recording devices of this class with certain novel and improved features and details of construction, which contribute toward rendering the devices preferable in use, as to certain particulars at least, to other devices for the same general purposes hitherto provided. The improvements may, for example, be applied with benefit to volt, ampere, watt, pressure and other measuring appliances or devices where it is desired to produce a permanent chronological record of measurements.

In the accompanying drawings the improvements are illustrated in connection with a thermo-electric pyrometer wherein the records are produced on a chart by a pyrometric pointer under the action of a striker which, in its turn, is caused by clock-work to operate periodically.

Referring to the drawings—Figure 1 is a face view of a chronometric pyrometer provided with the improvements, a part of the chart, and carbon paper employed therewith, being broken away to expose details which would otherwise be hidden; Fig. 2, an enlarged, broken and partly sectional view showing details of the mechanism; Fig. 3, an enlarged section on line 3 in Fig. 1; Fig. 4, an enlarged sectional view illustrating the construction of a clamp on the hour-shaft or arbor of the clock-work for holding the chart and carbon paper; Fig. 5, an enlarged perspective view of a striker-actuating cam mounted on the minute shaft or arbor of the clock-work; and Fig. 6, an enlarged broken section taken on line 6 in Fig. 1.

The mechanism is all inclosed in a suitable

casing 10 having a removable front 11. In 55 the front is a large opening 12 which is closed by a disk or face-plate 13. Surrounding the disk or face-plate 13, which is fastened to the front by screws, is a door-frame or bezel 14, hinged at 15, and fitted with a 60 glass 16. The door when closed is fastened by a lock 17. Mounted in the casing is a suitable clock-work of the type having a balance wheel escapement and two main-springs on winding-posts 18, 18. The 65 numeral 19 designates the hour-shaft or arbor of the clock-work and 20 the minute-shaft or arbor.

Mounted against the back 10 in the lower part of the casing is the permanent magnet 70 21 and attendant current-measuring mechanism, in circuit with the binding-posts 22 on the casing, which operate in the usual manner to swing the pointer 23, under changes of temperature of a thermo-couple 75 (not shown) the leads of which are connected to the binding-posts. Also mounted against the back 10 is a frame 24 having bearing ears 25, 25, for a rock-shaft 26, forming part of a striker-frame. The 80 striker-frame consists of the said shaft 26, rods 27 and 28 fastened to the shaft, a segmental bar or striker 29 mounted on the rods and a counterbalancing weight 30 fastened to the shaft. Surrounding the shaft 8 26 and connected at one end therewith and at its opposite end to the striker-frame support is a return spring 31. On the end of the pointer 23 is a head formed on its rear side to present an anvil 32 and provided in 90 its forward side with a socket or sleeve 33 to receive a hard metal stylus or marker 34, which works through a segmental slot 35 in the face-plate 13. Fastened to the minute-shaft 20 is a double cam 36 rotating against 95 the bent end of the rod 27 of the striker-frame.

Under changes of temperature of the thermo-couple employed, the pointer 23 is 100 swung to the right and left along the striker-bar 29; the position of the stylus 34 indicating the temperature at the couple in accordance with the scale 37 marked upon the face-plate. The pointer 23 is of spring metal and is held normally retracted; while the striker-frame is held against the cam 36 by the spring 31. In the construction shown, the cam 36 is given one complete

revolution each minute and each of its cam faces operates to retract the striker-frame away from the pointer head or anvil 32 until an abrupt shoulder 38 passes and releases 5 the rod 27 when the latter is swung to the advanced position indicated in Fig. 5, causing the bar 29 of the striker-frame to engage and force the stylus or marker 34 through the slot 35 until stopped by the 10 platen or impact surface formed by the glass 16.

The chart or record sheet 39 is in the form of a disk and is of translucent paper having printed upon its obverse surface accurate 15 chronological and temperature scales which may be, for example, as illustrated in Fig. 1. Placed against the reverse face of the chart is a similar disk 40 of paper, or the like, faced with carbon, or other printing 20 material, which is preferably of a color contrasting both with that of the translucent paper and that of the printed scales thereon.

The hour-shaft 19 (see Fig. 4) has a reduced threaded extension 41 and shoulder 25 42. On the extension, and clamped against the shoulder 42 by a nut 43, is an externally threaded sleeve 44 on which is screwed a cup-shaped clamping-member 45. The clamping-member 45 is formed with an annular 30 clamping face or edge 46 which is preferably serrated or milled to render it rough. The numeral 47 designates a removable cup-shaped clamping-member which fits into the clamping-member 45 and screws upon the 35 thread of the sleeve 44. It has an annular clamping-flange 48 coöperating with the clamping-face 46 of the member 45. The clamping-member 45 projects through an opening in the plate 13 to a plane but 40 slightly beyond the front surface thereof. The disks or sheets 39, 40, are provided with central openings just large enough to receive the cup-portion of the clamping-member 47, whereby they may be clamped between the 45 parts 46, 48, of the clamping-members. To place the disks in position the clamping-member 47 is removed from the sleeve 44 and the disk 39 and then the disk 40 placed thereon. The clamping-member is then re- 50 placed upon the sleeve and tightened to clamp the disks at their centers to rotate with the hour-shaft. To facilitate handling and turning of the clamping member 47, it is provided with the cross-extending pin 49. 55 Of necessity there should be but little space between the plate 13 and glass 16, though the space should be sufficient to permit the disks to rotate without material friction against either said plate or glass. The 60 clamping members 46, 47, constructed as described, hold the disks with sufficient firmness, and the flange 48, being of thin metal, takes up but little room between the surfaces of the parts 13, 16.

65 In operation the pointer 23, as before

stated, is positioned along the temperature scale in accordance with the temperature at the thermo-couple, as usual in devices of this class, and every half-minute the striker-frame is actuated by the cam 36, as before 70 explained, to press the stylus 34 carried by the pointer against the rear face of the carbon sheet 40. This presses the chart against the platen formed by the glass 16 and a mark is made upon the rear face of the 75 translucent chart which is visible through the latter and the glass 16. Immediately after the pointer is thus actuated the cam 36 starts to retract the striker away from the pointer and permit the latter to retract, so 80 that the mark in each instance is merely a dot. These dots being formed each half-minute produce a practically continuous line, at every point recording upon the chart the temperature and the time at which the mark 85 was made.

Among the advantages incident to our improvements are that by the use of charts of translucent paper, carbon paper may be employed as described, dispensing with 90 either ink or the lamp-black coated or chemically prepared papers hitherto commonly used in making records; one or a plurality of chart and carbon sheets may be placed in the device so that, if desired, a plurality of 95 records, often found desirable, may be made simultaneously; as the pointer and striker mechanism are located behind the chart, nothing stands in front of the latter to obstruct the view of any part thereof while 100 it is in the device; the counterweight 30 operates to balance the striker-frame so that the device will operate at any angle; the charts being of translucent paper, blue prints may be readily made therefrom when 105 desired; and all the working parts are back of the face-plate 13, so that there is no danger of disturbance or injury thereto when charts are inserted or removed.

We have stated that the chart or record 110 sheet should be translucent, and the most desirable paper for this purpose that we have employed is what is called "Bavarian parchment" in the trade. This paper though translucent in character is suffi- 115 ciently opaque to hide to a great extent the color of the carbon sheet placed against its reverse side. Any mark from the carbon sheet upon its reverse side is clearly visible 120 however at its obverse surface. The chart while in the device, and by reason of the transparent platen, thus serves as a plainly visible indicator as well as a record.

The foregoing description is intended to 125 convey a clear understanding of our improvements in what we now believe to be the best form of their embodiment, and no undue limitation should be understood therefrom. It is our intention to claim all that 130 is novel in our invention, and that the claims

shall be construed as broadly as the prior state of the art will warrant.

What we claim as new and desire to secure by Letters Patent, is:

5 1. In a device of the character described, the combination of record-marking mechanism, comprising a marker, shifting and actuating mechanisms for the marker, means for holding a carbon, or the like, sheet in front of said marker and a translucent record-sheet in front of said carbon-sheet, and a transparent platen in front of said record-sheet, whereby the record is produced against the resistance of the platen through 10 the carbon-sheet upon the reverse surface of the record-sheet, and the record is exposed to view, simultaneously with its production, at the obverse surface of the record-sheet unobstructed by the marker, and the translucent sheet serves to hide the carbon-sheet, for 15 the purpose set forth.

2. In a recording device of the character described, a casing, a face-plate forming the front-wall of the casing, clockwork in the 20 casing having a slowly rotating and a quickly rotating arbor, pyrometric mechanism in the casing having a pointer, a platen in front of and spaced from the face-plate, record-sheet-engaging means in said space 25 operatively connected with the slowly rotating arbor, a record-producing marker on the pointer working through an opening in the face-plate, a striker in the casing coöperating with the marker to press the same into 30 mark-producing relation with the record-sheet, and periodic actuating means for the striker operatively connected with said quickly rotating arbor.

3. In a recording device of the character 35 described, a casing, a face-plate forming the front wall of the casing, clockwork in the casing having a slowly rotating and a quickly rotating arbor, pyrometric mechanism in the casing having a pointer, a platen 40 in front of and spaced from the face-plate, a clamping device operatively connected with the slowly rotating arbor projecting through the face-plate into said space for engaging a record-sheet at the central portion thereof, a record-producing-marker on 45

the pointer working through an opening in the face-plate, a striker in the casing coöperating with the marker to press the same into mark-producing relation with the record-sheet, and periodic actuating means for 55 the striker operatively connected with said quickly rotating arbor.

4. In a recording device of the character described, a casing, a face-plate forming the front wall of the casing, clockwork in the 60 casing having a slowly rotating and a quickly rotating arbor, pyrometric mechanism in the casing having a pointer, a transparent platen in front of and spaced from the face-plate, means for holding a translucent record-sheet and a carbon, or the like, sheet in the space between the face-plate and platen, and operatively connecting them with the slowly rotating arbor, a record-producing-marker on the pointer working 65 through an opening in the face-plate, a striker in the casing coöperating with the marker to press the same in the direction of the platen against the reverse surface of the carbon sheet, and periodic actuating means 70 for the striker operatively connected with said quickly rotating arbor.

5. In a recording device of the character described, a casing, a face-plate forming the front wall of the casing, clockwork in the 75 casing having a slowly rotating and a quickly rotating arbor, pyrometric mechanism in the casing having a pointer, a transparent platen in front of and spaced from the face-plate, a clamping device on the 80 slowly rotating arbor projecting through the face-plate in lieu thereof, for holding a record-sheet and carbon or the like, sheet at the central portions thereof, a record-producing marker on the pointer working 85 through an opening in the face-plate in the direction of the platen a striker in the casing for the marker and an actuating cam for the striker on said quickly rotating arbor.

ALBERT L. MARSH.
JOSHUA PATRICK.
